UNITED STATES PATENT OFFICE.

PHIL M. PENNINGTON, OF BELLEVUE, TEXAS.

CUT-OUT DEVICE FOR WINDMILLS.

1,270,320.

Specification of Letters Patent. Patented June 25, 1918.

Application filed November 27, 1917. Serial No. 204,226.

To all whom it may concern:

Be it known that I, PHIL M. PENNINGTON, a citizen of the United States of America, residing at Bellevue, R. F. D. #2, 5 in the county of Clay and State of Texas, have invented new and useful Improvements in Cut-Out Devices for Windmills, of which the following is a specification.

The invention relates particularly to an 10 improved attachment for wind mills, whereby the mill may be thrown out of gear automatically when the supply tank becomes filled.

Another feature of the invention resides 15 in the provision of a latch for the lever which throws the mill in gear, this latch being conjoined with the weight that is rendered operative to release the latch only when the float carried within the tank is 20 lifted by the water which fills the latter.

Still another feature of the invention is the provision of a device of this character which is simple in construction, durable and effective in operation and which can be 25 manufactured at small cost.

Other and further features will be made apparent as the detail description of the device progresses.

To the exact construction in which the device is shown and described, the invention is not to be restricted. The actual reduction to practice may show certain changes or alterations to be desirable and these the right is claimed to make in so far as they do 35 not depart from the spirit of the subjoined claims.

In the accompanying drawings:

Figure 1 is an elevation of a portion of a windmill tower, showing the improved cut- 40 out mechanism attached thereto.

Fig. 2 is a view looking in the direction of the arrow in Fig. 1.

Fig. 3 is a section on the line 3-3 of Fig. 1.

45 Referring to the drawings in which only a portion of a windmill tower is shown, the arms 1 are attached by any suitable means to a post 2 of the tower, the lever 3 having one end pivotally mounted between these arms 1.

50 The lever 3 has attached to it the usual rod 4 which leads to the mill and is designed to throw the latter into or out of gear, depending on whether it is drawn down or raised. The rod 4 is connected to 55 the lever 3 at a point slightly to one side of the longitudinal center of the latter and

nearer to its pivotal connection with the arms 1 than to its free end. Thus as the lever 3 is moved from the horizontal position downward into the vertical position, the 60 rod 4 operates to throw in the clutch on the windmill, this portion of the windmill not being shown because it is not essential to an understanding of the invention. The conventional form of windmill clutch is ar- 65 ranged to stand normally in the inoperative position, so that this position tends to exert a pull on the rod 4 to raise the lever 3 to a horizontal position unless the latter is retained in the vertical position before re- 70 ferred to.

With the present invention a latch 5 is designed for attachment to the post 2 of the tower. This latch comprises a resilient plate having a right angled end 6 by means of 75 which it is attached to the end of the post, the plate further having a depression 7 formed in the upper face, in which depression the end of the lever 3 engages to hold the latter in the vertical position. On the 80 forward end of the latch but to one side, there is attached a weight 8, the end of a cable 9 being also attached at this point. The cable rises upwardly and passes over a pulley 10 rotatably mounted in a bracket 85 11 which is attached to the post 2 of the tower. From the pulley 10, the cable 9 passes to a second pulley 12 which is mounted in a bracket 13 that is attached on top of the water tank 14, the cable passing down 90 into the water tank and carrying at its end therein a float 15.

When the water tank 14 is empty, the float 15 remains suspended therein and is of greater weight than the weight 8. Therefore, this float exerts a pull on the cable 9 which keeps the latch 5 raised to its highest position. The windmill being in the inoperative position because of the lever 3 being raised so that the rod 4 does not exert 100 a force to keep the clutch engaged, the lever is depressed to the vertical position by hand and its free end made to engage in the depression 7 formed in the latch 5, in which depression it remains engaged and keeps 105 the windmill clutch in engagement because of the float 15 tending to raise the latch 5. The windmill then begins the pumping operation and delivers the water to the tank 14 (these connections not being shown be- 110 cause of being unessential to an understanding of the invention) which water, when

reaching a predetermined level in the tank, raises the float 15, thus allowing the weight 8 to exert the force of its weight on the end of the latch 5, depressing the latter and releasing the lever 3 which then rises to its horizontal position allowing the windmill clutch to be cut-out. It will be observed, that when the tank 14 is empty, it is only necessary to depress the lever 3 effecting 10 the engagement between it and the latch 5 before referred to. The filling operation then begins and no further attention is necessary, the windmill being thrown out of gear automatically when the tank 14 is 15 supplied with water to a predetermined level.

The invention having been described, what is claimed as new and useful is:

1. A cut-out device for windmills comprising a lever pivotally mounted on the tower of a windmill and having connection with the clutch thereof, whereby when the lever is horizontal the windmill is cut out and when the lever is vertical, the windmill 25 is in the operative position, a latch attached to the tower of the windmill and having means for engaging the lever to hold

it in the vertical position, a water tank, a float therefor, and devices conjoined with the float and with the latch whereby, when 30 the tank is supplied with water to a predetermined level, the latch is automatically released from the lever.

2. A cut-out device for windmills comprising a lever pivotally mounted on the 35 tower of a windmill and having connection with the clutch thereof, whereby when the lever is horizontal the windmill is cut out and when the lever is vertical, the windmill is in the operative position, a latch attached to the tower of a windmill, the latch being resilient and having a depression 40 formed therein so that the lever may be engaged there-by and held in the vertical position, a weight attached to the free end of the latch, a water tank, a float therein, a cable connecting the float with the free end of the latch, and pulleys over which the cable passes, whereby when water reaches a 45 predetermined level in the tank, the latch is released from the lever.

In testimony whereof I affix my signature.

PHIL M. PENNINGTON.
